UNITED STATES PATENT OFFICE.

ARCHIBALD C. DAVIS, OF NEWARK, OHIO.

SANITARY APRON.

1,311,759.

Specification of Letters Patent. Patented July 29, 1919.

Application filed November 5, 1918. Serial No. 261,307.

To all whom it may concern:

Be it known that I, ARCHIBALD C. DAVIS, a citizen of the United States, and a resident of Newark, in the county of Licking and State of Ohio, have invented a new and Improved Sanitary Apron, of which the following is a full, clear, and exact description.

My invention relates to a device for use 10 more particularly by a person needing to have recourse to a public toilet, and is designed to afford protection against infection or the contamination of the person or clothing.

15 Various shields have been proposed, designed to be laid upon the toilet seat, but drawbacks attend the use of these, in that they present difficulties in adjusting them to be fully protective; they cannot always be 20 made to conform to the seat, considering the varying forms of seats provided in different places; and the placing of the shield is attended with inconvenience on speeding railway trains, for example, due to air currents tending to displace the shield.

25 The general object of my invention is to provide a protector for the indicated purpose, in the form of an apron to be worn at the back of the user and adapted to be conveniently applied when required, by slipping it beneath the outer shirt, between the latter and the under clothing, and then securing the apron in position by suitable means, such as tapes or strings thereon, to be passed about the waist and tied; as well as to give the apron a divided form by the provision of an elongated vertical opening therein, so that the wearer of the apron, in the act of seating himself on the toilet, and 40 by spreading and otherwise disposing the underclothing, unfailingly positions the apron to be fully protective of the person and clothing against direct contact with the seat.

45 More specific objects are to provide an appendage to the apron at the lower end of the opening to insure complete frontal protection to the user when seated.

The stated objects and others as will appear, are attained in the manner hereinafter particularly described.

Reference is to be had to the accompanying drawings forming part of this specification, it being understood that the drawings are merely illustrative of one practical example of the invention.

Figure 1 is a rear view of a sanitary apron embodying my invention;

Fig. 2 is a transverse vertical section on line 2--2, Fig. 1;

Fig. 3 is an enlarged fragmentary rear perspective view of the lower portion of the apron at the opening, as well as the appendage for affording frontal protection; and

Fig. 4 is a fragmentary longitudinal vertical section of the front portion of a toilet seat and the lower portion of the apron in position on the seat.

In carrying out my invention in accordance with the illustrated example, the apron 70 10 is given suitable general shape and dimensions, the upper part having the lesser width and the lower portion presenting an area to extend below and at the sides of the buttocks when the apron is worn by a person at the back.

An elongated vertical opening 11 is formed in the apron at the center, said opening terminating short of the top and bottom of the apron. Any suitable fastening means is provided, preferably consisting of tie strings 12 which are adapted to be passed about the waist of the wearer from the back, and tied at the front in a bow knot.

85 In order to insure frontal protection to the user of the apron, I provide an auxiliary protector 13 on the apron at the outer side at the lower end of the opening 11. Said protector 13 is in the form of a flap so 90 formed and applied as to extend partially along the sides of opening 11 and about the lower end thereof, to lie approximately parallel with the outer surface of the apron, the arrangement being such that said flap 95 overlies the lower portion of the apron below and adjacent to the opening in a manner that when the wearer of the apron is seated on the apron the said flap will project forwardly at the underside of the seat, 100 centrally of the latter, while the lower portion of the apron will lie on top of the seat.

105 From the foregoing it will be readily understood that the apron may be slipped beneath the outer shirt and tied about the waist, whereby when the undergarments are spread and the wearer seated the proper positioning of the apron on the seat is insured without special adjustment to the 110 seat, and complete protection of the person and clothing is assured.

Any suitable material may be employed in the manufacture of the apron, but advantageously I employ rubber-coated or like moisture-proof material, with the moisture-proof surface outermost.

I would state in conclusion that while the illustrated example constitutes a practical embodiment of my invention, I do not limit myself strictly to the details herein illustrated, since manifestly the same can be considerably varied without departure from the spirit of the invention as defined in the appended claim.

Having thus described my invention, I claim as new and desire to secure by Letters Patent:

A sanitary protector comprising an apron adapted to be worn by the user, at the back,

and be secured at its upper portion, said apron having an area to be sat upon by the wearer and presenting an elongated approximately central opening terminating short of the top and bottom of the apron, to permit the apron to be given a divided form beneath the wearer when the latter assumes a sitting posture, together with an auxiliary protector on said apron at the outer side at the lower end of the opening therein, the material of the apron below the opening extending beneath said protector, and said protector being adapted to project forwardly beneath the toilet seat at the center, while the adjacent portion of the apron lies on top of said seat.

ARCHIBALD C. DAVIS.
